UNITED STATES PATENT OFFICE.

HEINRICH BECKER, OF KIEL-HASSEE, GERMANY, ASSIGNOR TO FRIED. KRUPP AKTIENGESELLSCHAFT GERMANIAWERFT, OF KIEL-GAARDEN, GERMANY.

COMPRESSED-AIR STARTING DEVICE FOR INTERNAL-COMBUSTION ENGINES.

Application filed May 12, 1924, Serial No. 712,880, and in Germany June 2, 1923.

This invention relates to devices for starting internal combustion engines by means of compressed air, and it has more particularly reference to devices of this kind in which the 5 valve gear automatically enters into or out of action upon the compressed air being admitted and stopped.

In a known device of this kind shown in U. S. Patent No. 1,418,583, after the passage 10 to the starting valve of the cylinder has been opened by manipulation of the starting lever, the starting air works on a control piston which operates the starting valve. The control piston is restrained by a lever whose motion is controlled by a cam.

In order to secure a noiseless and mechanically perfect operation of the valve gear it is necessary to cause the cam roller of the restraining lever to continually follow the 20 outline of the cam. This may be attained in the above mentioned device by making the control piston, which is under the pressure of the compressed starting air, of dimensions so large that it will constantly press 25 the cam roller against the cam disc. But, in such case, the valve would open even if the pressure in the working cylinder were still higher than the pressure of the starting air at the moment the motion of the restraining 30 lever was permitted by the cam, thereby destroying the fundamental feature of the above mentioned device.

The present invention has for its object to provide a device which prevents a premature 35 opening of the starting valve and yet insures a constant contact of the cam roller with the cam disc during the starting operation.

This object is attained by providing a lost 40 motion connection between the controlling piston and the starting valve and by providing for the application of fluid pressure to the starting valve itself just sufficient to open it when the compression in the cylinder 45 has dropped to the pressure of the starting air, while the pressure on the controlling piston keeps the cam end of the restraining lever in constant contact with the cam, this being permitted whether the starting valve 50 opens or not, because of the above mentioned lost motion connection.

The subject matter of the invention is il-

lustrated by way of example in the accompanying drawing in which

Fig. 1 is a vertical section of one embodiment of the invention and,

Fig. 2 is a vertical section of another embodiment.

The device illustrated in Fig. 1 will be described first.

In a cylinder head A of an internal combustion engine is disposed a valve cage B of a compressed air starting valve d'. Compressed starting air is led through the cylinder head to the valve by a conduit a'. In 55 the upper end of the bore of the valve casing the controlling piston C is mounted for vertical reciprocation. A small cylinder c' is connected to the lower end of piston C by a short neck c². On the upper end of the 60 valve stem D is mounted a piston d⁴ which reciprocates in the cylinder c'. The space above piston d⁴ is in communication with the space above the controlling piston C through a bore c³, and both spaces are connected by means of a pipe M to a source of compressed air of constant pressure such as the compressed starting air for example. A spring E which is inserted between the valve cage B and the lower face of the cylinder 65 c' tends to hold the starting valve closed.

A valve lever H which is mounted for 70 rocking motion on the shaft G has an arm h' which is forked at its end to embrace the neck c² of the piston C, while the other arm 75 of the lever H carries a roller h² which bears against a cam K, k'. The upper and lower surfaces of the forked end of lever arm h' are spherical to provide for the relative motion of the piston C and the lever H.

In order to describe the operation of the device it will be assumed that the starting valve should open when the pressure in the working cylinder has sunk below 285 pounds per square inch. The pressure of the starting air is assumed to be 355 pounds per square inch and the total pressure on the starting valve from within the cylinder at 285 pounds per square inch is 2650 pounds, for example. The diameter of the piston d⁴ which is connected with the valve stem is of such a dimension that the greatest pressure of the compressed air transmitted to it is likewise about 2650 pounds. The diam-

eter of the controlling piston C is such that the pressure exerted by the same on the arm h' of the valve lever through the influence of the compressed air acting on the piston C 5 is about 3300 pounds or more.

Now, when the recess k' of the cam disc K moves past the cam roller h² while the pressure in the working cylinder is higher than 285 pounds per square inch, the cam 10 roller h² will be pressed by the controlling piston C into the recess of the cam disc, but since the pressure on piston d⁴ is not great enough to overcome the pressure on the valve d', the valve will remain closed and 15 the cylinder c' will simply move downward with relation to the piston d⁴, compressing the spring E. If, on the other hand, the pressure in the working cylinder is less than 285 pounds per square inch when the recess 20 k' moves opposite the roller h², the pressure on the piston d⁴ will be sufficient to overcome the pressure on the valve d' and the valve will therefore move downward with the piston C and cylinder c'. In either 25 case the cam roller h² is constantly held against the cam disc K by the action of the controlling piston C throughout the operation, and therefore the opening of the valve will take place without the valve lever being subjected to any sudden movements or 30 shocks.

The pressure in the working cylinder against which the starting valve d' should be opened can be determined at will; it is 35 only necessary that the pressure exerted by the compressed air on the piston d⁴ be suitably controlled, which may be attained by the use of pressure reducing valves or the like.

40 The only essential difference between the embodiment shown in Fig. 2 and that of Fig. 1 is that in the former the controlling piston C is itself constructed as a compressed air cylinder in which the piston d⁴ reciprocates, whereby a material simplification is attained as will be readily understood.

Having described my invention, I claim:

1. In a compressed air starting device for internal combustion engines, comprising a starting valve, a valve gear adapted to automatically enter into and out of action upon admitting and stopping the compressed air and a controlling piston included in said gear, a pressure cylinder and a second piston inserted between the controlling piston 50 and the stem of the starting valve, the diameter of said second piston being of a dimension such as to cause the pressure exerted on it to open the starting valve, independently on the movement of said valve gear, upon a determined pressure prevailing in the engine cylinder, and the diameter of the controlling piston being of a dimension such as to cause the pressure exerted on it by the compressed starting air 55 to outweigh the pressure of the said second piston.

2. In a compressed air starting device for internal combustion engines, comprising a starting valve, a valve gear adapted to automatically enter into and out of action upon admitting and stopping the compressed air and a controlling piston included in said gear, a pressure cylinder and a second piston inserted between the controlling piston and 70 the stem of the starting valve, the diameter of said second piston being of a dimension such as to cause the pressure exerted on it to open the starting valve, independently on the movement of said valve gear, upon a determined pressure prevailing in the engine cylinder, and the diameter of the controlling piston being of a dimension such as to cause the pressure exerted on it by the compressed starting air 75 to outweigh the pressure of the said second piston.

The foregoing specification signed at Hamburg, Germany, this 23rd day of April, 90 1924.

HEINRICH BECKER.
